UNITED STATES PATENT OFFICE.

ROBERT W. SCOTT, OF BOSTON, MASSACHUSETTS, ASSIGNOR, BY MESNE ASSIGNMENTS,
TO SCOTT & WILLIAMS INCORPORATED, A CORPORATION OF MASSACHUSETTS.

MACHINE FOR KNITTING THICKENED-WALE FABRICS.

Application filed August 10, 1916. Serial No. 114,096.

This invention relates to knitting machines, an object of the invention being to provide, in addition to the usual functions of such a machine, for knitting a longitudinal mark, wale or ridge having therein an additional or thickening yarn, and characterized by relative opacity as compared with the body-fabric, and if desired by an intermittent or interrupted structure imitating a sewed seam.

Heretofore fabrics having longitudinal marks or ridges, as for clocks, mock seams and similar uses, have been formed either by varying the knitting as by tucking, drop-stitching or other weakening changes of texture without thickening the fabric at the mark, or by adding an embroidery or sewing yarn to the fabric after its completion; and one purpose of this improvement is to provide for making marks, seams or thickened wales of this nature without creating in the fabric any structure tending to weaken the fabric and without necessitating two operations, the machine concurrently forming the fabric and making the seam or ridge. This invention therefore provides, in a machine having the usual devices for the production of an article such as a stocking, means for additionally producing in the article, at predetermined parts thereof, a mock seam, ridge or mark characterized by the presence of an additional or thickening yarn.

For the above or other purposes this invention also provides means for feeding to a limited segment of the needles of a circular knitting machine an additional yarn in such a manner as to cause said yarn to extend continuously longitudinally of the fabric, and alternately to engage the fabric formed by one or the other of said needles at and between, or near, the wales of loops formed upon said needles.

This invention further provides for feeding an additional yarn for a mark, ridge or mock-seam, in such a manner as not to interfere with splicing the fabric by the ordinary agencies employed for that purpose, for instance agencies for producing a high splice partly around the ankle, at the back thereof and above the heel in a seamless stocking.

This invention therefore comprises in a knitting machine of the kind having knit-

ting and splicing yarn feeding devices, 55 means for also feeding an additional yarn, the respective yarn feeding means being adapted and arranged to cooperate together without interference for the performance of their respective functions. 60

The invention is illustrated in connection with a circular knitting machine of the general type shown in my United States Letters Patent No. 1,148,055, dated July 27, 1915, and in my application for Letters 65 Patent of the United States Serial No. 66,424, filed December 13, 1915 (Patent No. 1,282,958 dated October 22, 1918), but it will be understood that my invention is independent of the particular machine to which 70 it is applied, being of general application to knitting machines having relatively movable yarn feed devices and needles.

In the accompanying drawings—

Figure 1 is a development of the needle cams in an illustrative circular machine, showing one embodiment of this invention;

Figure 2 is a side elevation of a circular knitting machine illustrating one form of automatic devices for feeding the thickening yarn and other yarns; 80

Figure 3 is a partial plan view above the latch ring, parts being in section on the line 3—3 of Figure 2;

Figure 4 is a plan above the cam ring of 85 the knitting machine shown in Fig. 2, showing some of the needles, and one device for rendering the production of the thickened place intermittent;

Figures 5 and 6 are respectively a detail 90 under plan of an instrument dial and a section on the line 6—6 of said instrument dial illustrating provisions for floating the additional yarn across the needle circle;

Figure 7 is a vertical section on the line 95 7—7 of Fig. 4;

Figure 8 is a view illustrating the different kinds of needles employed;

Figures 9, 10, 11, 12, 13 and 14 are diagrams illustrating the relations of the different yarns to each other and to the needles. 100

Figure 15 is a view illustrative of a stocking employing the new structure as a mock seam at the back of the leg; and

Figure 16 is a diagram of one form of the 105 fabric.

Referring to Figs. 1, 2 and 4, a circular machine having therein a cylinder or car-

rier 260 for needles n of the usual construction may be employed. In the ordinary operation of the machine, relative movement in the direction of the arrow N between needle carrier 260 and the cam ring or carrier 271, Figs. 1 and 4, having thereon the usual knitting cams 357, 360, 361, results in moving the needles to knit the usual plain knit fabric having a new course of loops formed at each passage of all of the needles past the stitch cam 360, 361. As illustrated in Figs. 1 and 16, knitting may so take place at each of the needles in turn at the following stitch cam 360 from a body yarn k . The needles n may, as shown, be latch needles of the ordinary form, some of them, see Figs. 4 and 8, having long butts n' , and some of them having shorter butts n'' , for the usual purpose of enabling one set, the long butt needles for instance, to be placed out of action and out of range of any of the cams 357, 360 and 361, during reciprocal knitting, as for heel and toe pockets, on the remaining needles n'' .

26 A predetermined segment of the needles, as shown at n^3 may be arranged to be operated differently from the remainder as by providing them with butts shorter than the others, for the purpose of applying to them a different yarn t to form a mock seam or thickened wale, one species of which is shown at 2, Fig. 16.

15 In the machine illustrated, needles which have been actuated to knit, for instance at cam 360, are returned to an intermediate level 40, at which their latches are not cleared through their previous loops, so that in order to knit said needles must be further advanced before receiving yarn and 40 before being depressed to a lower point than the intermediate level 40 for the purpose of knitting.

45 The machine improved may comprise means cooperating with a movable splicing yarn guide s' to cause some of the needles, for instance those having the shorter butts n'' to take in addition to the yarn k at the time of their knitting at cam 360 an additional splicing yarn s , the devices cooperating 50 with the splicing yarn guide s' being such as to cause said splicing yarn guide to remove its yarn above the passing needles except when the segment of needles to receive the splicing yarn is passing the yarn 55 guide, the splicing yarn by this means being caused to float across the circle of needles from one end to the other end of the segment of needles n'' . This float usually defines a diameter or substantially a diameter 60 of the circle of needles.

65 The yarn k is also fed from a movable yarn guide k' ; and this yarn may be substituted for, exchanged, or accompanied by another yarn according to the arrangement of the machine, for instance, by removing the

yarn guide k' from the operative position shown in Fig. 1, and by entering the yarn guide k^4 or k^5 carrying another yarn or yarns into operative position to feed yarn into the hooks of the needles. Guide k^4 may be that guide operatively positioned during heel and toe knitting.

Devices for working the yarn guides for the above purpose are not a new part of the present invention, but may, as disclosed in my said patent, comprise a series of thrust bars 460, Fig. 2, operated by cams on a pattern drum 120 intermittently moved, for instance, throughout one whole revolution during the making of each article. The motion of the splicing yarn guide s' into and out of operation during each revolution of the cylinder 260 may be caused as usual by a cam 296 rotating with said cylinder reacting on a lug a on that bar 460 cooperating with the yarn guide s' .

Without disturbing the above-indicated old art arrangements, the present invention provides for isolating a segment of the needles, for instance the needles n^3 having the shortest butts, from their neighboring needles, and for winding upon said needles a wrapping of a continuous additional yarn t , during knitting of a predetermined extent of fabric. While this yarn is continuous during production of this extent of fabric, its application to the needles n^3 may be intermittent.

Any suitable means for isolating the needles to receive the yarn t may be provided. As illustrated, at a part of the cam-ring 271 following the stitch-cam 360, a depression 41 of the ledge or level 40 is provided wherein all of the needles n except the segment n^3 may be depressed below their normal idle level on ledge 40. It will, however, be understood that the needles to be isolated might be projected from a series of needles n all held at a lower level than normal, or that in some cases the needles n might be abnormally elevated and all of them except the needles to receive the additional yarn then be depressed; or that the needles to receive the additional yarn might be elevated from the normal level at which the other needles are permitted to remain. In any case, all of the needles at the level 40, preceding the illustrated depression 41, have upon their open latches loops of the yarn k interknit with a previous course cast off at cam 360. Any of these needles may thus be depressed at 41 without casting off their last loop.

Any convenient means for depressing all the needles n , except the needles n^3 may be employed. One preferred means comprises an auxiliary cam 100 carried conveniently, as on a resilient spring arm 101 having a depending lug 102, Figs. 1 and 7, adapted to be bent to adjust with respect to cam-ring 100.

271 the inward position of the cam 100 under stress of spring arm 101. Spring arm 101 is made fast to ring 271 at a relatively remote point, as at the screws 103, Fig. 4. 5 Cam 100 is beveled at its forward end 105 to form a depressing slope for such needles as encounter it, but its inner vertical face is beveled outwardly at its rear end at 106, Fig. 4, so that arm 101 and cam 100 can 10 yield outwardly upon reversed relative motion of the parts when the beveled face 106 is struck by a needle of any length of butt traveling at the level 40. By this means cam 100 is rendered active to depress such needles as encounter it in the direction of arrow N only.

The normal position of cam 100, as shown in Figs. 4 and 7, is such as to cause its depressing slope 105 to encounter and depress 20 all of the needles except the needles n^3 having the shortest butts. These needles n^3 pass across the face of cam 100 at the normal level 40, and thereby stand above the other needles throughout the extent of the depression 41.

When intermittent operation of the needle-isolating devices 41, 100 with respect to the needles n^3 is desired (the lug 102 being adjusted as shown to permit cam 100 to 30 move inward to affect all of the needle-butts), positive means for moving cam 100 outwardly at intervals then to permit needles n^3 to pass across its face are provided, said means, for instance, moving the cam 100 35 outwardly to its normal position during three or four successive courses, and permitting the cam 100 to move inwardly to depress all of the needles during one or more following courses. One convenient device 40 for this purpose is that illustrated in Fig. 4, a lever 420 pivoted at a remote point (not shown) above and to the right of the figure being operated to move on the arc f against a pin 107 projecting from cam 100, so that 45 in the normal position illustrated cam 100 is withdrawn outwardly to pass the needles n^3 without depressing them. Lever 420 may occupy this position normally, being withdrawn at intervals of the desired number of 50 courses in the direction of the arrow f', or left stationary for as long as desired. Means for so operating such a lever 420 forms no new part of my present invention, being fully disclosed in my application Serial No. 853,053, filed July 25, 1914 (Patent No. 1,311,623 dated July 29, 1919). When lever 55 420 is withdrawn, spring-arm 101 moves cam 100 as far inward as permitted by lug 102. In this position, all of the needles are 60 depressed by cam 100, but this is without result on the fabric formed of the body-yarn k.

In case intermittent operation of the needle-isolating devices at intervals of a few 65 courses only is not desired, the lug 102 may

be so bent as to limit cam 100 from further inward movement than sufficient to depress all of the needles except the needles n^3 , and the lever 420 need not be employed; or the lever 420 may be left in the position shown. 70 In either case the cam 100 is free to yield outwardly against stress of spring-arm 101.

The additional yarn t is supplied by a movable yarn-guide t' during formation of the desired predetermined part of the article only, an automatic operating connection, preferably to the pattern surface or drum 75 120, controlling the operative and inoperative positions of said movable guide t'.

Referring now to Figs. 1, 2 and 3, guide 80 t' may be a thin resilient strip of metal having suitable yarn eyes therein fastened to one end of a bent lever T pivoted at 554, for instance on the same stud as the other yarn-guide levers k', k⁴, s', etc. A spring t² normally elevates the guide t', the rear end t³ of the lever T then standing above a bar t⁴ guided for vertical movement in a hole in a plate t⁵ fast to a fixed part of the machine. The lower end of bar t⁴ is received in a 85 notch t⁶ of one of the thrust-bars 460, for instance that one employed to operate yarn-guide k⁴ for the heel and toe yarn, or another yarn-guide or movable part whose connection 460 is normally elevated at the times 90 intended for operative position of the guide t'. Lever T and guide t' may now be depressed by giving to bar 460 an extra elevating movement above the range of movement suitable for moving out of operation 95 the part usually operated by it, such as yarn-guide k⁴. As shown, cams 501 of one height on drum 520 move the yarn-guide k⁴ out of operative position, and a more elevated part 100 502 on the same ring of cams serves to move lever T and guide t' into operative position at another predetermined part of the knitting. The connection t⁴ is readily removable 105 from the machine.

Lever T is so formed as to bring the yarn-guide t' forming a part thereof substantially into the relative position with respect to the needle circle, the cam 100 and depression 41, and the remaining yarn-guides illustrated in 110 Figs. 1, 3, and 9 to 14. As best shown in Figs. 1 and 3, the guide t' is arranged to deliver yarn t beneath the line swept by hooks of the needles moving at normal level 40. To permit access of the guide t' to this position, a depression or gap d is formed in 115 the cylindrical inner surface of the usual latch-guard ring 550. A movable gap-closer ring 565 substantially as illustrated in my said Patent No. 1,148,055 is provided with an opening 62 to receive guide t' and with beveled points 63 to bridge gap d when any of the needles are elevated for reciprocal knitting.

Referring now to Fig. 1, whenever the cam 100 is in its normal position the needles 130

n^3 are isolated but remain at their normal level, so that these needles receive the yarn t when they pass the yarn-guide t' , the remaining needles having passed down the slope 105 and being depressed in the depression 41. None of the needles except the needles n^3 encounter the yarn t . The effect of this is illustrated in Figs. 9 to 14. In Fig. 9 for instance a group of needles n^3 is shown at I approaching the yarn-guide t' . These needles having taken the yarn t in their hooks, will pass to position II, the yarn t extending in an increasing chord of the circle, the yarn t being drawn out in the direction of the arrow g until the yarn t extends across a diameter of the circle of the needles n , as shown in Fig. 11. During the remainder of the relative motion of the group of needles n^3 with respect to the yarn-guide t' the yarn t is recovered through the yarn-guide t' in the direction of the arrow g' .

To permit the yarn t to be drawn off and recovered in this manner, it may be fed through an ordinary spring take-up device, not shown, of any suitable sort.

The needles n^3 take the yarn k and knit at the cam 360 in a normal manner. It will be observed that the yarn t has been taken upon these needles in their hooks, or upon their opened latches, but prior to receiving the yarn k for a new knitting course the needles n^3 were advanced, along with the other needles at the upper surface of the cam 361, and thereby cleared the yarn t beneath their open latches so that the yarn t is in the position of the knit loops of the last course. This insures that the yarn t shall be cast off of the needles n^3 without being interknit by them. Referring to Fig. 16, the only engagement of the yarn t thus received by the needles n^3 , which knit the wales b, a', b in said figure, is with the yarn of the sinker-wales between the wales b and normal wales a of the body fabric.

Continued revolution of the needles n^3 with respect to the yarn-guide t' produces a continuous wrapping of the yarn t about the needles n^3 in a direction contrary to the direction of rotation of the needles n , as illustrated by the arrow w in Fig. 11. At the knitting point 360 in each revolution this wrapping is cast off over the head of the needles, being replaced by another turn prior to the passage of the needles n^3 on the next revolution at the cam 360.

That portion of the yarn t drawn off and recovered during each revolution appears in the fabric as a float y extending from the engagement of the yarn t in one sinker-wale to the engagement of the yarn t in another sinker-wale, beyond the wales b, a', b from the needles n^3 in the next course.

That part of the yarn t which was placed upon the face or hook side of the needles n^3

at their passage by the guide t' and subsequently cast off from these needles, extends at the back of the fabric as shown at y' in Fig. 16.

If now all of the needles, including the needles n^3 , are depressed into the depression 41 at passage by the yarn-guide t' the yarn t will not be received by any of the needles and will float across the intervening course or courses of the yarn k as illustrated at y^4 , Fig. 16.

If the yarn t is fed under suitable tension, as by the employment of any known tension device, the wales b, a', b of the body fabric will be puckered or projected above the surface of the fabric.

While I have shown for one instance a group of three needles n^3 , it should be understood that the said needles may be employed in any desired small number, for instance, one, two or ten. In each case the effect of the relative rotation of the needle circle will be to wind the yarn t about the needle or needles n^3 and to cast it off along with the previous course loop upon knitting at the cam 360.

When it is desired to form in the fabric a spliced area such as illustrated at h in Fig. 15, the yarn-guide s' is lowered to an operative position during the passage of the segment of needles, for instance during the passage of the shorter butt needles n^2 , guide s' , being thrown upwardly during the passage of the remaining needles to form the diametrical floats of the yarn s illustrated in Figs. 13 and 14, as usual. For this purpose during the knitting of the parts of the article not spliced, the yarn s may as usual be clamped as at 7, Fig. 9, above an internal plate or dial 5, the yarn-guide s' being above or within the circle of needles. Under these circumstances the float t , Fig. 9, is free to pass under the plate 5 without encountering the yarn s .

I have shown by way of example of the application of my device to the machine of my said application Serial No. 66,424, in Figs. 5 and 6, an internal plate 5 covering an instrument-dial 4 provided with a sloped boss 3 and a cutaway portion 20 adapted to guide the floated yarn t beneath the respective structures 3, 4 and 5. The instrument-dial 4 in this case rotates in unison with the needles in the direction of the arrow on Fig. 5. The cutaway portion 20 extends behind the position of the needles n^3 so that the float of the yarn t may readily enter under the dial 4.

If now the guide s' is moved from its position illustrated in Fig. 9 to the position illustrated in Fig. 10 to begin feeding its yarn to the leading needle n^2 , it will be observed that the yarn t will not encounter the splicing yarn s , the needles n^3 and the yarn t moving in the successive positions in Figs. 10, 11 and 12. The yarn t on the needles n^3

will have been cleared beneath their latches at the point 361, Fig. 11, and the yarn *s*' will have been taken into the hooks of these needles and knit thereby at the point 360, at 5 which time the end of the run of yarn *t* is at the backs of the needles and engaged at its point of exit from the last course.

At the time indicated in Fig. 12 the yarn-guide *s*' again moves to the inoperative position, but at this time, before the float of 10 the yarn *s* can reach it the needles *n*³ will have passed the yarn-guide *t*'. When the yarn *s* made its exit from the fabric it did so with respect to a cast-off course lying at 15 the back of the needles and in a relatively low position. The float of the yarn *s* will therefore enter under the yarn *t*, as shown in Fig. 13, and the yarn *t* will remain above the floated yarn *s* as illustrated in Fig. 14, during 20 the remaining half revolution. The yarns will continue to pass in succession as illustrated in Figs. 12, 13 and 14 respectively so long as the splicing yarn is fed.

It is not necessary that all of the needles 25 *n*³ should be adjacent to each other. The needle for knitting the wale *a*', Fig. 16, may, for instance, be one of the needles *n*². In that case the passage of this particular needle *n*² to the level 40 after traversing the depression 41 will bring the needle *n*² in front 30 of the wrapping of the yarn *t* received by the needles *n*³. In this case the yarn *t* passes to the back of the fabric in each of the wales *b* from the needles *n*³, but is engaged only 35 with the sinker-wales respectively between wales *a* and *b* and *b* and *a*'.

Formation in the fabric of the thickened mark 2 begins and ends upon movement of 40 yarn-guide *t*' into and out of operation, as predetermined by the position and extent of cam 502, Fig. 2. When thrust-bar 460 leaves the end of said cam, the yarn *t* is withdrawn upwardly, whereupon rotation of its point of attachment to the fabric causes this yarn 45 to pass about the devices above the plate 5, as shown in Fig. 3, until the end of the yarn *t* is received under the clamp 7 and severed by the cutter 16 of the usual kind.

As shown in Fig. 15, the mark 2 may imitate 50 a sewed seam at the back of a seamless tubular stocking, and in that case may be begun at any point at or beneath the top or hem and end above the heel.

It should be observed that the arrangement 55 of devices by which the yarn *t* is engaged with the fabric without entering the knit loops enables the fabric to be made without providing means for increasing the length of the stitches in the wales knit by 60 the needles employed for forming the mark or thickened wale. Otherwise, it would be impracticable to knit upon the same needles the yarns *k*, *s*, and *t* without breakage. The machine may include the usual devices for 65 increasing the length of the body-yarn loops

in the area *k*, but special provision for lengthening the stitches of needles *n*² need not be made.

By the described means, the yarn *t* is engaged with the fabric so as to lie wholly on 70 one face of the fabric, said yarn *t* being concealed by the loops of the yarn *k*, or the yarns *k* and *s*. The yarn *t* may differ in kind or quality from either or any of the other yarns. 75

What I claim is:

1. A knitting machine having therein a series of needles, means for feeding a body yarn and a splicing yarn to and knitting at 80 said needles, means for isolating one or more of said needles, and means operative wholly at one side of the series of needles by relative movement between said means and series for placing a wrapping of a continuous additional yarn on said isolated needle or 85 all of said isolated needles prior to knitting on said needles or any of them.

2. A knitting machine having a series of needles, stitch cams, and a means for feeding a body yarn to and knitting at said needles, means for causing a narrow segment of the needles to stand at a higher level than other needles at a place remote from the stitch cams, and means operative wholly at 90 one side of the series of needles by relative movement between said means and series to place upon said narrow segment of needles in position to be cast off unknit at the stitch cams a wrapping of additional yarn. 95

3. A knitting machine having therein needles, means for feeding a body yarn to and knitting at said needles, means moving the needles in the direction of their lengths for isolating one or more of said needles, and means for placing a wrapping of a continuous additional yarn on said isolated needle or 100 needles in a position to be cast off unknit when the next subsequent course of body yarn is knit thereat.

4. A knitting machine having therein longitudinally movable needles, means for feeding a body and a splicing yarn to and knitting said yarns at said needles, means for causing one or more of said needles to be isolated by movement of some of the needles 110 to a different position from the others, and means operating wholly at one side of the series of needles by relative movement between said means and the needles for placing a wrapping of a continuous additional 115 yarn on said isolated needle or needles in a position to be cast off unknit when the next subsequent course of body and splicing yarn is knit thereat. 120

5. A knitting machine having a series of 125 needles and automatic means for knitting thereon from a body yarn and a splicing yarn a predetermined extent of fabric, in combination with a guide for an additional yarn operating wholly at one side of the 130

series of needles by relative movement between said means and series for placing on some of the needles at predetermined times in the operation prior to knitting on them a 5 wrapping of an additional yarn.

6. A knitting machine having in combination needles and means for knitting thereupon of a body yarn a body fabric, and means operative during knitting for engaging 10 with the body fabric and alternately on each side of one or more needle-wales without interknitting an additional yarn, said yarn being free from engagement with the fabric at all other parts of the same course 15 and extending from course to course longitudinally of the fabric.

7. A knitting machine having needles and automatic means for knitting thereon from a body yarn a predetermined extent of fabric, 20 in combination with means for placing on some of the needles and for operating the needles to cast off unknit from the needles at predetermined times in the operation a wrapping of an additional yarn.

25 8. A knitting machine having needles, yarn feed means and cam devices adapted to act on all of the needles to knit a body fabric, in combination with means for feeding an additional yarn, and a cam device for 30 moving all of said needles except certain isolated needles out of range of said additional yarn, whereby to form on said isolated needles a wrapping of said additional yarn adapted to be cast off with the last knit 35 course.

9. A knitting machine having a series of needles, a stitch cam, and a yarn-feed guide for knitting body fabric, a guide for an additional yarn adapted to be held stationary 40 when in operation, and a needle isolating device cooperating with said additional yarn-guide for wrapping about a narrow group of the needles only an additional yarn, and subsequently operating means adapted to engage said additional yarn with 45 the body-yarn of a subsequent course only.

10. A knitting machine having latch needles, a stitch cam, and a yarn-feed guide for knitting body fabric, an additional yarn-guide, and a needle isolating device 50 cooperating with said additional yarn-guide for arranging upon some of the needles only above their latches an additional yarn, and means acting on the needles to clear the 55 needle-latches from said additional yarn acting prior to the formation of the next knit course on said isolated needles.

11. A circular knitting machine having therein a series of knitting needles knitting 60 cams and a cooperating knitting yarn-guide, means for isolating one or more of the needles at a point remote from the knitting cams, and a yarn-guide operative in fixed relation to said isolating means adapted to 65 deliver additional yarn to said isolated needles.

dles only above their latches, in combination with means for causing relative rotation between said needles and the respective yarn-guides and means for clearing the latches of said additional yarn prior to moving 70 them to knit at the knitting cams.

12. A circular knitting machine having yarn-feed means, a circular series of latch needles, a stitch cam, and means for maintaining the needles between passages of the 75 stitch cam at an idle level in which the loops are not cleared beneath the latches, in combination with an auxiliary cam adapted to depress from said idle level all of the needles except certain isolated needles, and 80 means for feeding an additional yarn to engage said isolated needles, whereby said additional yarn floats across the circle of needles between passages of said needles and their feeding means. 85

13. A knitting machine having a series of needles, a body yarn-guide and a stitch-cam adapted and arranged for single-course knitting, in combination with means acting on the needles between successive passages of 90 the stitch-cam to isolate one or more needles from the other needles, and a feed guide operative at a point fixed in relation to said isolating means whereby to feed an additional yarn to said isolated needle or needles 95 only in such relation as to be cast off of said needle or needles at the next passage of the stitch cam.

14. A knitting machine having a series of needles, a body yarn guide, a splicing yarn 100 guide, a stitch cam, and means acting on the needles to knit the body yarn and the splicing yarn at the stitch cam, in combination with means acting on the needles between successive passages of the stitch-cam to isolate one or more needles from the other needles, a feed guide adapted to feed an additional yarn to said isolated needle or needles only in such relation as to be cast off at the 105 next passage of the stitch cam, and means 110 for rendering said yarn guide for the additional yarn operative and inoperative at a point fixed in relation to said isolating means at predetermined times.

15. In a knitting machine, means for knitting a body yarn and means for knitting a sectional reinforced or spliced area of a body-yarn and a splicing-yarn, in combination with means for engaging an additional yarn at or near the center of said reinforced 120 area. 115

16. A knitting machine having needles and devices for feeding and knitting a body-yarn, means for feeding to a segment of the needles only and interknitting a splicing 125 yarn, and means for engaging without interknitting an additional yarn with the fabric to produce a longitudinally-extending thickened mark.

17. A knitting machine having needles 130

- and devices for feeding and knitting a body-yarn, means for feeding and interknitting a splicing yarn at a segment only of said needles, and means for engaging without interknitting an additional yarn with the spliced portions of the fabric to produce a longitudinally-extending thickened mark in the spliced portions of the fabric. 65
18. A stocking knitting machine having 10 needles and devices for feeding and knitting a body-yarn, means for feeding and interknitting a splicing yarn at a segment of the needles only during knitting of certain parts of the stocking, and means for engaging an 15 additional yarn with the fabric to produce a longitudinally-extending thickened mark in the spliced and unspliced portions of the stocking. 70
19. A knitting machine having in combination needles, a stitch-cam, and means for feeding body and splicing yarns, in relation to the stitch-cam for knitting thereat, in combination with means for feeding an additional yarn to certain of said needles only at 25 a point remote from said stitch-cam during splicing whereby said additional yarn is engaged with the spliced fabric without being interknit therein. 75
20. A knitting machine having a circle of 30 needles and devices adapted to feed and withdraw a splicing yarn, whereby said splicing yarn floats substantially diametrically across the needle-circle, in combination with means for simultaneously feeding 35 to a segment of the needles and floating across the circle an additional yarn, and means for knitting fabric engaging said additional yarn. 80
21. A knitting machine having means for 40 knitting body fabric, means adapted to engage at the back of the fabric without interknitting with said fabric an additional yarn in successive courses, and means adapted to prevent such engagement at intervals whereby 45 to produce a thickened interrupted mark imitating a looper-sewed seam. 85
22. A knitting machine having means for 50 knitting body fabric, means adapted to engage at the back of the fabric without interknitting with said fabric an additional yarn in successive courses during knitting of a predetermined extent of the fabric, and means adapted to prevent such engagement at intervals of one or more courses during 55 the knitting of said predetermined extent of fabric. 90
23. A knitting machine having needles, a stitch cam and a cam adapted to selectively act upon the butts of said needles to isolate certain needles, means for feeding an additional yarn to the isolated needles in position to be cast off unknit at the stitch cam, and automatic means causing said cam at times to act upon all of the needles, where- 95
- by to prevent taking of said additional yarn at said times. 100
24. A knitting machine having needles and a movable cam adapted in one position to selectively act upon the butts of certain needles to isolate other needles, means for feeding to the isolated needles, and for casting off therefrom unknit an additional yarn, and automatic means for moving said cam into another position to act upon all of the needles, whereby to prevent taking of said additional yarn at times. 105
25. A knitting machine having in combination needles with operating butts of different lengths, body yarn feeding means and a stitch-cam means for feeding a splicing yarn to be interknit at said stitch-cam, means for normally retaining the needles between passages of the stitch-cam at an intermediate level, means for isolating needles having one length of butt comprising a movable depressing cam adapted to depress all of the needles except those having that length of butt, the said cam being adapted to pass all of the other needles at said level and means for laying upon the 110 isolated needles an additional yarn. 115
26. A knitting machine having needles with operating butts of different lengths, a stitch-cam means for feeding a splicing yarn to be interknit at said stitch-cam and means for normally retaining the needles between 120 passages of the stitch-cam at an intermediate level, in combination with a depressing cam for isolating needles having one length of butt adapted to engage and move out of said level all of the needles except those having that length of butt, the isolated needles being adapted to pass said cam at the normal level and means for laying an additional yarn on the isolated needles. 125
27. A stocking knitting machine adapted for rotary and reciprocatory knitting and having needles with operating butts of different lengths, stitch-cams, and means for normally retaining the needles between 130 passages of the stitch-cams at an intermediate level, in combination with means for isolating needles having one length of butt comprising a cam adapted to engage and move out of said level all of the needles except those having that length of butt, said cam being adapted to yield to an inoperative position in one direction of relative movement between said needles and said cam. 135
28. A circular stocking knitting machine 140 adapted and arranged for knitting on a circle of needles a seamless stocking having heel and toe pockets formed on a segment of said needles, and having means for knitting a high-spliced area above the heel, in combination with means cooperating with needles of said segment to engage an additional yarn in the fabric, whereby to form 145

a thickened mock-seam at the back of the leg, said seam extending into the spliced area.

29. A cam device for knitting machines comprising a resilient arm rigidly mounted at one end, a needle cam mounted on said arm, and a lug on said arm adapted to be bent to determine by contact with a fixed part one position of said cam.

30. A movable auxiliary cam device for circular knitting machines comprising a cam carrier, a resilient arm thereon, a beveled needle cam mounted thereon whereby said cam can yield when approached by needles in one direction, said cam being normally held by said arm in one position, and positively acting means acting in a direction angular to a radius of the machine and adapted to engage a projection from said arm and cam for changing the position of said cam.

31. A knitting machine having a series of needles, body yarn-guides, a stitch-cam, and yarn severing means for the withdrawn body yarns, in combination with means acting on the needles between passages of the stitch-cam to isolate one or more needles from the other needles, and an auxiliary yarn feed guide adapted to feed to and withdraw from said isolated needles an additional yarn, said additional yarn when withdrawn being positioned to be received and severed by said severing means.

32. A knitting machine having therein needles, a stitch cam, means for knitting body-fabric thereon, and means for feeding to certain of the needles an additional yarn for engagement with the body-fabric to form a longitudinal thickened wale or mark, said means comprising a movable yarn guide, a pattern-surface, and a connection from said

surface for moving said yarn-guide into and out of a fixed position in range of and at one side of the needles at a point remote from the stitch cam at predetermined times.

33. In a knitting machine yarn-feeding devices comprising a movable yarn-feed guide for a body yarn, a thrust-bar for moving said body-yarn guide, a pattern surface, and cam means thereon for normally moving said thrust-bar to move said body-yarn guide into and out of operative position, in combination with a movable yarn guide for an additional yarn, a connection between said additional yarn guide and said thrust-bar, and means for moving said thrust-bar to a different extent from its normal movement to work said additional guide.

34. In a circular knitting machine having needles and an instrument-dial relatively fixed with respect to the needles in a rotary sense, and having yarn-feed means with respect to which and said needles and dial there is relative rotary movement, means for permitting a yarn floated across the needle-circle from isolated needles to pass under said dial comprising a cut-away face on the under side of said dial following in the direction of relative rotation the position of said isolated needles.

35. In a circular knitting machine having needles and an instrument-dial mounted within the needles, and means adapted to cause a yarn or yarns to be removed within the circle of needles, means for permitting such yarn or yarns to float freely under said instrument-dial comprising a conical projection or boss at the under side of said dial.

Signed by me at Boston, Massachusetts, this seventh day of August, 1916.

ROBERT W. SCOTT.
